UNITED STATES PATENT OFFICE.

ADDISON V. SMITH, OF CORTLAND, NEW YORK.

MILK-CAN.

SPECIFICATION forming part of Letters Patent No. 595,822, dated December 21, 1897.

Application filed April 9, 1897. Serial No. 631,462. (No model.)

To all whom it may concern:

Be it known that I, ADDISON V. SMITH, a citizen of the United States, residing at Cortland, in the county of Cortland and State of New York, have invented a new and useful Milk-Can, of which the following is a specification.

This invention relates to certain improvements in milk-cans, and especially that class of milk-cans used for holding milk to be retailed; and the object of the invention is to provide a milk-can of a simple and inexpensive nature adapted for use by retail milk-dealers, the device being so constructed as to permit of draining substantially all the milk from the can without requiring the can to be tipped to pour out the milk therefrom.

The invention consists in a milk-can having its bottom formed with a depending marginal flange and a central cup-like depression or chamber the cross-sectional area of which is less than that of the mouth of the can and a dipper comprising a cup having a handle and of a size to fit into said cup-like depression in the bottom of the can.

The invention also contemplates certain novel features of the construction, combination, and arrangement of the parts of the improved can, whereby certain important advantages are attained and the device is made simpler, cheaper, and otherwise better adapted for use, all as will be hereinafter fully set forth.

The novel features of the invention will be carefully defined in the claims.

In order that my invention may be the better understood, I have shown in the accompanying drawings a milk-can embodying my improvements, in which drawings—

Figure 1 is a perspective view showing the under side of the improved can; and Fig. 2 is a transverse section taken axially through the improved milk-can, showing the dipper and cover of the can in position. Fig. 3 is a transverse section taken through the can in the plane indicated by the line *a a* in Fig. 2, and Fig. 4 is a perspective view showing the dipper employed in connection with the improved can.

In the views, 1 indicates the body portion of the improved milk-can, this being made, as shown in the drawings, of a cylindrical form

and being provided with a reduced neck portion 2, connected with the upper part of said body 1 by means of a tapered or beveled shoulder 3, the arrangement of the parts being such that the mouth of the can is aligned with the axis of the cylindrical body portion 1 thereof.

The can is provided with a bottom 4, which is made saucer-shaped or convexed on its upper surface, as clearly shown in the sectional view Fig. 2, so that the central portion of said bottom is at a lower level than the marginal edges thereof, and said edges of the bottom are connected with the inner sides of the body portion 1 at a point considerably above the lower edges of said body portion, so that said lower edges of the body portion project below the bottom 4 of the can and form a depending marginal flange extending around the lower part of the can and forming a foot or base upon which the can rests. If desired, the edge of said depending flange or foot 5 may be reinforced in any preferred way, and in practice I prefer to form the body portion 1 of the can with a bead 6, extending around it and pressed outward, so as to form a recess, as clearly shown in Fig. 2, wherein the marginal edges of the saucer-shaped or convexed bottom 4 of the can are held. I do not, however, desire to limit myself to the exact construction of these parts shown, since it is evident that the foot or base 5 may be formed independently of the body portion 1 of the can.

The neck 2 of the improved can is formed with a flange 6^a at its upper edge, and this flange forms a flared mouth at the upper end of said neck, and said mouth is adapted to be closed by means of a cover comprising a cap or plate 7, having a convexed under side and of circular form, said plate being of a diameter greater than the flanged portion of the neck, so as to fit closely over the same, and being provided with a handle 8 on its upper side and with a tubular body portion 9, projecting centrally from the under side of said cap and adapted to fit centrally in the neck 2 of the can.

At the center of the saucer-shaped bottom is formed a cup-like depression or chamber 10, as clearly shown in Figs. 2 and 3, this chamber being formed of a circular casing

having a closed bottom and having its upper edges secured to the edges of a circular opening formed in the bottom 4 of the can in such a way that said casing projects below the under side of said bottom within the space inclosed by the depending marginal flange 5 at the lower part of the can.

In connection with the improved milk-can, constructed as above described, I employ a dipper, (shown in detail in Fig. 4,) this dipper comprising a cup 11 of a size and shape to fit within the cup-like depression or chamber 10, formed in the bottom of the can, and being of such a depth that when it is arranged in said chamber its upper edge will be substantially flush with the upper surface of the bottom 4 of the can, so that the milk within the can will flow over its upper edges and into the cup. The cup is provided with a pouring-lip 12, extending part way around its edge, so that the milk can be conveniently poured from the dipper, and with a handle portion 14, projecting upwardly from one side of said cup and arranged to project up adjacent to the flared mouth of the can, as shown in Fig. 2, when the cup of the dipper is inserted in said chamber 10 in the bottom of the can. By preference the handle portion 14 of the dipper is secured to the edge of the cup 11, at one end of the lip 12 thereof, so that the milk can be conveniently poured from the dipper, and a part of the edge of said cup will be left free to permit the milk to run from the bottom of the can over the same and into the cup.

From the above description it will be seen that the improved milk-can is of an extremely simple and inexpensive nature and is especially well adapted for use by retail milk-dealers, since it permits substantially all of the milk contained in the can to be removed therefrom without necessitating the tipping of the can to pour out the milk. The improved milk-can is also especially adapted for use by milk-peddlers, and when made especially for this purpose it will usually be preferable to provide the can with a bail 15, secured at its ends to lugs 16, projecting from opposite sides of the upper portion of the body of the can, so that the can can be conveniently carried about. It will also be obvious from the above description that the in-

vention is capable of some modification without material departure from its principles and spirit, and for this reason I do not wish to be understood as limiting myself to the precise form and arrangement of the various parts herein set forth.

Having thus described my invention, I claim—

1. A milk-can comprising a shell, and a flared bottom which is provided with a central depression, forming a receptacle in vertical alinement with the open mouth of the can, combined with a dipper having its cup fitted in the receptacle and serving as a means for removing any contents of the can which may drain thereto, substantially as set forth.

2. In a milk-can, a bottom provided with a central depression forming a chamber, and united to the shell of the can on a line considerably above the lower edge thereof, to provide a marginal flange that depends below the bottom and its depression to form a base whereon the can may rest, combined with a dipper arranged within the can to have its cup fit the central depression in the bottom, whereby all the contents of the can may be removed without tilting or inverting the can, as and for the purpose described.

3. A milk-can consisting of a body portion having a neck at its upper part and provided with a bottom extending across its lower portion above its lower edge, the lower edge of the body portion projecting below said bottom and forming a base or foot whereon the can rests, and said bottom being formed with a central cup-like depression or chamber extending down within the space inclosed by said base or foot, in combination with a dipper having a cup of a size and form to fit within said cup-like depression and of a depth such that its upper edge is substantially flush with the bottom of the can, and a handle secured to said cup and arranged to extend up adjacent to the mouth of the can, substantially as set forth.

In testimony that I claim the foregoing as my own I have hereto affixed my signature in the presence of two witnesses.

ADDISON V. SMITH.
